No. 826,253.

PATENTED JULY 17, 1906.

T. B. JEFFERY.

SPARKER IGNITER RETARDING DEVICE FOR GAS ENGINES.

APPLICATION FILED JAN. 9, 1905.

UNITED STATES PATENT OFFICE.

THOMAS B. JEFFERY, OF KENOSHA, WISCONSIN.

SPARKER-IGNITER-RETARDING DEVICE FOR GAS-ENGINES.

No. 826,253.

Specification of Letters Patent.

Patented July 17, 1906.

Application filed January 9, 1905. Serial No. 240,228.

To all whom it may concern:

Be it known that I, THOMAS B. JEFFERY, a citizen of the United States, residing at Kenosha, in the county of Kenosha and State of Wisconsin, have invented new and useful Improvements in Sparker - Igniter - Retarding Devices for Gas-Engines, of which the following is a specification, reference being had to the accompanying drawings, forming a part thereof.

The purpose of this invention is to provide an improved means for adjusting the igniting-spark in an electric igniter for gas-engines suitably at starting by means of the movement of parts which are necessarily operated at starting the motor.

It consists of the features and characteristics of construction set out in the claims.

In the drawings, Figure 1 is a detail plan view showing certain parts of a motor-vehicle, and the gas-motor thereof having the features and elements constituting my invention. Fig. 2 is a sectional elevation showing more fully the parts of the structure seen in Fig. 1, the vehicle-frame being shown in transverse section. Fig. 3 is a section at the line 3-3 on Fig. 2.

For the purpose of understanding my invention the particular construction of the vehicle and motor is immaterial, except in certain specific features, and the general construction will therefore not be explained, except in so far as it is directly related to the parts constituting the invention.

It is well understood that the time of "sparking" in a gas-motor being varied with respect to the time of maximum compression of the explosive gas in the compression-stroke of the piston will cause variation in the power developed by the explosion and the consequent speed attained by the motor, and that for the maximum efficiency the spark should be produced at such time that the resultant combustion or explosion may take place at the instant of maximum compression, and that in order to obtain this result the circuit should be closed for causing the spark a little before the instant of maximum compression. It is also well understood that when the engine is operating slowly, as at starting, if the spark is produced before the instant of maximum compression—that is, before the piston has completed its inward stroke—the explosion is

liable to occur before that stroke is completed, so causing the motion of the engine to be reversed, because the motor will not have momentum enough to complete the stroke against the initial force of the explosion. It is therefore well understood that it is necessary to adjust the sparking device so that at starting the spark should not be produced until the piston has completed its return stroke and the crank has passed the center, so that the explosion will with certainty continue the rotation in the proper direction. The expedient for adjusting or regulating the time of sparking which I employ in connection with the present invention consists in making one of the contact-points of the sparking device adjustable in the path of the other contact-point, so that it may be set back or forward in said path to retard or advance the spark, and the present invention consists, broadly, in connecting this adjustable contact-point with the means which are employed and practically necessary in all cases for relieving the cylinder of a part of the explosive charge at starting, so that the operator may be able to start the engine by hand, as he might not be able if the usual full charge were contained in the cylinder without relief and had to be compressed to the maximum. The device for thus relieving the cylinder of a portion of the explosive charge may accomplish this result in various ways.

In the drawings the rocking-lever 1, suitably mounted upon any fixed portion of the structure, is the lever which operates the exhaust-valve, which must be opened to relieve the cylinder, the connections to the exhaust-valve being made from the end 3 of the lever, the opposite end of the lever having the roller 4, which bears upon the valve-operating cam 5 of the shaft 6, which makes one revolution for two revolutions of the main shaft and whose complete revolution therefore corresponds to the full cycle of the engine's action, such engine being understood to have the customary four-cycle action. The cam 5, it will be noticed, has one prominence 5^a, so that the valve as controlled by this cam is open but once in the entire cycle—namely, at the exhaust-stroke of the piston. Alongside this cam on the same shaft and most conveniently of one piece with the cam 5 is a supplemental cam 7, which has two prominences 7^a and 7^b at substantially opposite positions,

the former being of the same height as and continuous with the prominence 5^a of the cam 5 and the latter being of less height. The rocking lever 1 is movable longitudinally 5 of its pivot—that is, transversely with respect to the lever—and is provided with a spring 8, tending to hold it in the position at which its roll is on the cam 5; but if it is pushed laterally against the resistance of the 10 spring the roll will pass over onto the cam 7, and the lever will then be operated so as to open the exhaust-valve not only at the usual exhaust-point, but also at the compression-point; but the prominence 7^b, operating for this second opening, being less than the 15 prominence 7^a, gives the valve only a partial opening, and therefore only relieves a portion of the pressure instead of permitting full exhaust, the relief being, however, designed to be sufficient to render it possible for the operator to operate the engine by hand, while obtaining an explosion of sufficient force to continue the movement thus started. For forcing the lever 1 laterally, so as to shift it onto 20 the cam 7, there is provided a wedge 9, suitably mounted by means of a slot 9^a on the stud 1^a, on which the lever 1 is fulcrumed, and having its diverging faces operating, respectively, against one side of the hub of the 25 lever and against the frame in which the stud is rotated. A rod or handle 10 extends from this wedge to any convenient point within reach of the operator, where it is lodged and sustained in the proper support 11, beyond which it may be provided with any convenient 30 form of handle, as the loop 10^b, so that the operator by pulling back the wedge may shift the lever off of the cam 5 and onto the cam 7. This will be done in all cases as a preliminary to starting the engine by hand.

12 12^x represent an element comprising a metal part 12 and an insulating part 12^x, which carries on the latter the movable contact-point 12^a for closing and opening the 35 circuit to produce the igniting-spark. This contact-carrying element is pivotally mounted by means of the metal part 12 upon the shaft 6, on which the coöperating contact-carrying element 14 is mounted for rotation.

50 The contact-carrying element has pivotally connected to its insulating part 12^x an operating-rod 15, suitably lodged and guided on the framework, extending alongside the rod or handle 10 of the wedge 9, and said rod or handle 10 has a sideward-jutting eye 10^a, through which the rod 15 passes, and said last-mentioned rod has stop nuts or collars 55 16 and 17 at opposite sides, respectively, of said eye, the stop-nut 17 being adjustable on the rod. When the operator pulls the rod 10 to operate the wedge 9 for the purpose explained, the eye 10^a encounters the stop-nut 17 on the rod 15, pulling that rod in direction 60 to cause it to swing the contact-carrying ele-

ment 12 forward in the direction of rotation 65 of the rotating contact-carrying element 14, so that it is not reached by said rotating element so early in the rotation of the shaft as it otherwise would be, and the spark is thereby retarded to that extent. The nut 17 may 70 be adjusted on the rod 15 as found necessary or most convenient to retard the spark the desired amount.

I claim—

1. In an explosive-engine, in combination 75 with the exhaust-valve-operating lever, two cams for operating said lever mounted side by side, the lever being movable laterally on its fulcrum to shift it from one cam to the other; a spring which holds it normally in position for coöperation with one of its cams; a wedge sliding on the fulcrum of the lever for crowding the lever laterally against the action of the spring, and a handle extending from said wedge for operating the same. 85

2. In an explosive-engine, in combination with the exhaust-valve-operating lever, two cams adapted to operate said lever, one of the cams being constructed for opening the valve once in the revolution of the cam and 90 the other being constructed for opening it twice, the lever being movable laterally on its fulcrum to shift it from one cam to the other; a spring tending to hold it in position for coöperation with the first-mentioned cam; 95 a wedge sliding on the lever-fulcrum tapered for crowding the lever against the tension of its spring to shift it to the second cam, and a handle extending from said wedge for operating the same at will. 100

3. In an explosive-engine, in combination with the exhaust-valve-operating devices, a bar movable at will for opening the exhaust-valve during the compression-stroke; a contact making and breaking device comprising 105 an adjustable element carrying one of the contact-pieces; a link connected to said adjustable element extending contiguous to said bar and coöperating stops on said link; a stop on the bar for communicating part of the motion of the bar to the link and providing for play between the bar and link with respect to the remainder of such motion. 110

4. In an explosive-engine, in combination with the exhaust-valve-operating devices, 115 means for causing the exhaust-valve to be partially opened during the compression-stroke to relieve the compression, said means comprising a rod or bar movable at will for such relief; a contact making and breaking device comprising a rotating and an adjustable element having coöperating contact-pieces, and connections from such adjustable element to the relief-bar, consisting of a link connected to the adjustable contact making 120 and breaking element and extending contiguous to the relief-bar, said relief-bar and link having, one of them two stops, and the other, 125

one stop intermediate the two, the stop on
the link which encounters a stop on the re-
lief-bar in the movement of the bar for relief,
being adjustable to vary the time of such en-
counter in the relief movement of the bar.

In testimony whereof I have hereunto set
my hand, in the presence of two witnesses, at

Kenosha, Wisconsin, this 27th day of De-
cember, 1904.

THOS. B. JEFFERY.

In presence of—

H. W. JEFFERY,
G. H. EDDY.
